Carpets

No. 11,512

Nov. 18, 1879

UNITED STATES PATENT OFFICE.

MILTON R. LOUDEN, OF HOBOKEN, NEW JERSEY, ASSIGNOR TO THE
BIGELOW CARPET COMPANY, OF CLINTON, MASS.

DESIGN FOR CARPET.

Specification forming part of Design No. 11,512, dated November 18, 1879; application filed September 18, 1879.
[Term of patent 3½ years.]

To all whom it may concern:

Be it known that I, MILTON R. LOUDEN, of Hoboken, in the county of Hudson and State of New Jersey, have invented a new and original Design for a Carpet, of which the following is a specification.

The accompanying photographic illustration represents a face view of my newly-designed carpet.

This invention relates to a new and original design for carpets, oil-cloths, and similar fabrics, and for the border of the same.

It consists of the new ornamentation and grouping of the figures hereinafter more fully described.

In the photographic illustration the letter A represents the body of my newly-designed carpet. B is the border thereof.

Upon the background of the body A are arranged a multitude of small pinnate leaves, a, apparently irregularly scattered. Between these small leaves a are interspersed a series of larger pinnated leaves, b, and small ro-

settes or flowers d, some arranged singly, others in groups of two and three.

The border B is divided into two stripes, f and g. The inner stripe, f, is ornamented by rectangular figures h and by rosettes i, which alternate with each other. The outer stripe, g, contains a series of nearly semicircular scrolls, j, each containing a central rosette, k.

I claim—

1. The design for a carpet, consisting of the figures a, b, and d, substantially as shown.
2. The design for the border of a carpet, consisting of the stripe f, having ornaments h i, and of the stripe g, having ornaments j k, substantially as shown.

3. The design for a carpet, consisting of the body A, having figures a b d, and of the border B, having stripes f and g, with figures h, i, j, and k, substantially as shown.

MILTON R. LOUDEN.
